FIG. 5.

UNITED STATES PATENT OFFICE.

EMANUEL SALOMON ULLMANN, OF NEW YORK, N. Y.

MOORING MEANS FOR DIRIGIBLES.

1,413,948.

Specification of Letters Patent. Patented Apr. 25, 1922.

Application filed March 3, 1921. Serial No. 449,377.

To all whom it may concern:

Be it known that I, EMANUEL SALOMON ULLMANN, a citizen of the United States, residing in the borough of Manhattan, city and State of New York, have invented certain new and useful Improvements in Mooring Means for Dirigibles, of which the following is a specification.

The invention relates to mooring means 10 for dirigibles, or any form of lighter than air craft.

The principal object is to provide a simple and cheap means of mooring the smaller types of privately owned sport craft.

15 A further object is to provide a mooring means that will be comparatively light in itself, but stayed in all directions to which a stress may be delivered, and at the same time, to present a sector of 90° each side of 20 the suspension or mooring point that will be free of stays or lines that would be liable to cause chafe or injury to the vessel moored.

A further object is to provide a mooring means consisting of a vertically disposed 25 mast or upright, the same being suitably stayed in a sector of not over 180°, the said stays being revolvably mounted in a manner to cause them to follow the line of stress and always maintain their center of effort diametrically opposite the said line of stress or point of suspension of the craft to be moored.

30 The old form of staying a mast with four or more stays, the same being equally disposed and fixedly secured over 360° would be unsuitable for this form of mooring, due to the danger of the stays injuring the craft when swinging in the wind or lowering to the ground.

40 With these and other objects in view, the invention resides in the various novel parts and devices combined, arranged, operated and co-operated as hereinafter described and claimed.

45 In the accompanying drawings, in which like reference characters indicate corresponding parts, and in which I have illustrated one embodiment of my invention:

50 Fig. 1 is a side elevation of the arrangement.

Fig. 2 is an enlarged view of a travelling stay trolley in which a section of the supporting track and the anchorage means for the same are shown.

55 Fig. 3 is a plan view of Fig. 2.

Fig. 4 is a view looking downwardly and forwardly on the mooring arrangement from the point of staying.

Fig. 5 is a sectional elevation of an enlarged view of the upper portion of the 60 mast.

The form of my invention I am about to describe is the present preferred form. I do not wish to limit myself, however, to this specific form, its proportions, sizes or materials; in fact, I reserve the right to make departures in the details here shown to meet the demands of commercial practice so long as I do not depart from the broad spirit of the invention as set forth in the annexed 70 claims.

In the embodiment of the improvement here shown, A indicates a mast or upright of any desired height or diameter, suitably embedded in concrete or other approved 75 mixture B. The mast is further fitted at its free end with a Y arm C, a thrust collar D, a ball race E, and a sheave head F. The Y arm C is revolvably mounted upon the thrust collar D and under certain conditions 80 free to be lowered or raised to any point of the mast between the point of its present disposition and the base. The said Y arm is further fitted with stay eyes G and supporting eyes H and a bell mouth end I, the latter being the point of suspension for the 85 craft to be moored. The sheave J and the line J¹ are obviously a fair leader sheave and mooring line. The thrust collar D is fixedly secured to the mast as indicated. The sheave 90 head F is revolvably mounted upon the ball race E and fitted with fair leader sheave F¹, F², F³, the first two mentioned being single and the latter double. Sheaves F¹ and F² are fitted with guide cheeks F⁴ and 95 F⁵. Sheave F³ has a flare mouth bill guide F⁶, the purpose of which to be hereinafter described. Raised a suitable distance from the ground and supported by any means such as rods K, is disposed a circular track 100 or support L, the center of which being the vertical center of the mast. While for convenience I have shown the track with a rectangular cross section, obviously it may be a slot or any desired conventional form. Loosely mounted upon this track I will 105 dispose any suitable number of stay sheaves M. In this form I have indicated three, and two sifter sheaves N, all five sheaves being disposed about equal distance apart and 110

disposed about equal distance apart and 110

rigidly connected by the rod or pipe O in a manner to cause any motion of one sheave to be transmitted to the other, the purpose being to cause all five sheaves and the stays secured thereto to move as one. Secured to the eyes M¹ are stays M² and turnbuckles M³, the opposite end of the stays being secured to the three eyes G of the Y arm C. Secured to the eyes N¹ of the shifter sheaves are turnbuckles N² and stays N³, the opposite ends of these stays being secured to the shifter arms C¹ and C² of the Y arm C, but in a manner to cause the stays to cross as shown. The revolvably and slidably mounted Y arm C is supported by the flexible means H¹, the said means being secured at H and passing over the single sheaves F¹ and F² and the double sheave F³, thence out through the bill F⁶ to the point of securing at the center stay sheave, all as shown. The stay sheaves M and the shifter sheave N are further fitted with back lash sheaves P for the purpose of preventing the stay sheaves from becoming disconnected from the track or slot in case of the sudden slackening of the stays.

The application of my invention is as follows: When a dirigible to be moored is sighted, the line J¹ may be payed out and made fast to the mooring line of the ship, the end of which will probably be dropped by the vessel. The line will then be hauled in until the nose of the ship is in the desired position, substantially as shown in Fig. 5. The arm C may be hoisted to any desired height upon the mast A and the topping lift line H' made fast to any part of the movable structure of the trolley wheels. The mooring arm will naturally be rotated to leeward so that the ship may approach to windward, assuming the ship moored as indicated in Fig. 1. As soon as the wind shifts the slightest degree the revoluble arm C is shifted by the tug of the ship and the shifter arms C¹ and C² are moved correspondingly, these arms in turn shifting the entire staying arrangement due to their connection therewith. The sheave head F which is loosely mounted upon the ball race E is in turn correspondingly shifted by the action of the topping lift lines H' bearing against the sheaves F¹ and F² and the side pull of the same lines further down against the bill guide F⁶ when the lines H' which are secured at their lower end to the revoluble trolley structure are rotated by the said structure. From this action it may be seen that the stays are constantly shifted as the wind shifts so that they are always directly to windward of the ship.

Having described my invention, its objects, advantages, etc., I claim:

1. In a mast support, the combination of a vertically disposed mast or spar fixedly secured, a plurality of horizontally shiftable stays for the said mast, means revolvably

mounted upon the mast and disposed substantially at right angles thereto, the said means being adapted to receive the upper ends of the stays at one end and a horizontally shiftable load at the other end, the said arrangement being for the purpose of automatically shifting horizontally the stays as the load is horizontally shifted. 70

2. In a mast support, the combination of a vertically disposed mast or spar fixedly secured, a plurality of horizontally shiftable stays for said mast, means revolvably and slidably mounted upon the mast and disposed substantially at right angles thereto, the said means being adapted to receive the upper ends of the stays at one end and a horizontally shiftable load at the other end, the said arrangement being for the purpose of automatically shifting horizontally the stays as the load is horizontally shifted. 75

3. In a mast support, the combination of a mast or spar, a slidably and revolvably mounted cross arm mounted upon the said mast or spar, a revoluble support for the said arm, stays connected to the said arm and means to automatically shift the said stays so that their center of effort will always remain diametrically opposite a shifting load disposed at right angles to the mast, the said load being secured to one end of the cross arm. 90

4. In a mast support, the combination of a mast or spar a slidably and removably mounted cross arm mounted upon the said mast or spar; one end of the said cross arm being adapted to the mooring of a dirigible, a revoluble support for the said arm, mast stays connected to the said arm, none of the said stays being disposed nearer than 90° in a horizontal plane to the mooring end of the said cross arm, means to horizontally rotate the said stays so that their center of effort will remain diametrically opposite the horizontally shiftable mooring end of the above mentioned cross arm. 100

5. In a mast support, the combination of a mast or spar, a slidable and revolvably mounted cross arm mounted upon the said mast or spar; one end of the said cross arm being adapted to the mooring of a dirigible, a revoluble support for the said arm, a plurality of mast stays connected to the said arm, none of the said stays being disposed nearer than 90° in a horizontal plane to the mooring end of the said cross arm, the said mast stays being rigidly connected to each other at the ground end, but being free to rotate in a horizontal plane, means to rotate the stays in a manner to retain their center of effort diametrically opposite the horizontally shiftable mooring end of the above mentioned cross arm. 115

6. In a mast support, the combination of a vertical mast or spar, a horizontally disposed circular mooring runway disposed at 120

- or near the base of the said mast or spar, trolleys mounted under the said runway, a slidably and revolubly mounted cross arm mounted upon the said mast or spar, a revolute support for the said cross arm, stays disposed between and secured to the said cross arm and the said trolleys and means for rotating the said stays horizontally as the said cross arm is horizontally rotated.
- 10 7. In a mast support, the combination of a vertical mast or spar, a horizontal circular runway disposed around the mast and equal distance therefrom, the same being at or near the base of the mast, anchoring means for the said runway, a plurality of trolleys mounted under the said runway, the same being disposed substantially equal distance apart over 180° of the said runway and rigid securing means for holding the trolleys 15 in fixed relation to each other, a slidably and revolubly mounted Y cross arm mounted upon the said mast, a revoluble support for the said Y arm, adjustable connecting means between the said Y arm and the revoluble 20 support, a back stay and side stays disposed between the said Y arm and the stay trolleys, cross shifter stays disposed between the diverging Y arms of the cross arm and the shifter trolleys, all as and for the purpose 25 described.
8. In a mast support, the combination of a vertical mast or spar, a horizontal circular runway disposed around the mast and equal distance therefrom, the same being at or near the base of the mast, anchoring means for the said runway, a plurality of trolleys mounted under the said runway, the trolley having double flanged wheels under the runway and plain back lash wheels over the runway, a connecting arm between the wheels,
- 15 two extension lugs for securing a connecting means between the trolleys and a stay eye, a slidably and revolubly mounted Y cross arm mounted upon the said mast, a revoluble support for the said Y arm, adjustable connecting means between the said Y arm and the revoluble support, a back stay and two side stays disposed between the said Y arm and the stay trolleys, cross shifter stays disposed between the diverging arms of the Y arm and the shifter trolleys, rigid connecting means between each trolley and turnbuckle in each stay.
- 10 9. In a mast support, the combination of a vertically disposed mast or spar, a slidably and revolubly mounted Y cross arm mounted upon the mast or spar, a sheave head hanger for the same, a ball bearing support for the sheave head, a support for the ball race, two single sheaves and one double sheave in the sheave head hanger, a flexible and adjustable connecting means secured to the Y cross arm, the same passing over the sheaves in the sheave head, the free ends of the flexible means being secured to the movable trolley 60 structure; side and back stays for the mast, a revoluble trolley structure for carrying the side and back stays, means for automatically shifting horizontally the trolley structure so that its center of effort will remain diametrically opposite the single leg of the Y arm, the latter adapted to shift horizontally; a mooring line in the single leg of the Y arm and a fairleader sheave, all as and for the purpose described.
- 15 In testimony whereof, I have signed my name to this specification, this 21st day of February, 1921.

EMANUEL SALOMON ULLMANN.
